United States Patent Office

Des. 225,210
Patented Nov. 28, 1972

225,210

BOTTLE

Kurt Becker, Obernkirchen, Germany, assignor to
Hermann Heye, Allee, Germany

Filed Aug. 25, 1970, Ser. No. 24,682

Claims priority, application Germany Mar. 6, 1970

Term of patent 14 years

Int. Cl. D9—01

U.S. Cl. D9—99

Fig. 1

Fig. 2

Fig. 3

FIG. 1 is an elevational view of a bottle showing my new design, the opposite side being the same in appearance as the side shown;

FIG. 2 is a bottom plan view; and

FIG. 3 is a top plan view thereof.

I claim:

The ornamental design for a bottle, substantially as shown and described.
